UNITED STATES PATENT OFFICE

ARTHUR F. CASE, OF CLEVELAND, OHIO, ASSIGNOR TO THE WELLMAN ENGINEERING COMPANY, OF CLEVELAND, OHIO, A CORPORATION OF OHIO

CAR-DUMPER CONTROL

Application filed January 10, 1927. Serial No. 160,038.

This invention relates to car dumpers of the lifting type, and has particular reference to the control of the hoisting mechanism for lifting the cradle in the frame of the dumper and for tilting or turning it to dump the contents of the car supported on the cradle.

As it is well known, in dumpers of this type the cradle which receives the car is moved upwardly to the point where the cradle is to be turned and the cradle is then turned about two pivots and dumps the contents of the car into a so-called discharge pan which is carried by a girder extending across the frame of the dumper and movable vertically in guides in order that the height at which the dumping takes place may be varied. Generally, the ends of the girder slide in two guides in the two front vertical corner posts of the dumper frame, and to raise and lower the girder and pan, the ends of the girder are provided with nuts which engage two long upright screws which extend up along the corner posts and which are adapted to be simultaneously turned in one direction or the other by suitable power operated means under control of the operator.

When the cradle reaches the point where turning movement is to begin, the axis of the turning movement is established by the engagement of a pair of pins which are carried at the front upper corners of the cradle with a pair of hooks or jaws which are provided on the girder near its ends, the pins remaining in engagement with the hooks during the forward and return turning movements.

In the operation of these car dumpers, it is desirable and at times necessary that the dumper handle a large number of loaded cars in a given time, making it necessary that the cycle of movements of each dumping operation, including the elevating of the cradle, its turning to dump, the return turning motion, and the lowering of the cradle take place in a short space of time. This makes it necessary that the cradle be elevated, turned in both directions and then lowered rapidly, but in the operation of these dumpers it is essential that near the end of the elevating movement of the cradle the latter be decelerated so that the cradle will come to an almost

dead stop when the pins engage the hooks to initiate the turning movement, also that the turning motion be quickly accelerated and then brought to a stop at the end of the turning motion; and that on the return motion the turning motion be accelerated and then decelerated near the end of the return turning motion, and then accelerated at the start of the lowering movement and finally decelerated and stopped in its normal car receiving position.

In most of these car dumpers in operation at the present time, the matter of accelerating and decelerating is controlled manually by the operator, generally by hand operated control of the motive means of the hoist mechanism, any other mode of operation being rendered difficult because of variables introduced by the adjustment of the pan girder, it being understood that the location or height of the pivots and hooks carried by the girder determines the times in the cycle of operation at which the decelerating and accelerating occur.

The principal object of the present invention is to provide means whereby the movement of the cradle can be controlled automatically, particularly in so far as the accelerating and decelerating of its movements are concerned regardless of the position of the pan girder and regardless of the fact that it is or may be adjusted vertically from time to time to suit loading conditions, as, for example, in loading a vessel with coal or other material.

This result is accomplished by my invention, which comprises a control mechanism which may involve one or more switches adapted to be operated by a part suitably connected to the cradle hoist mechanism, there being provided also a connection between a part of the control mechanism and the girder shifting mechanism so that the times or instants that the control mechanism functions to accelerate or decelerate the movement of the cradle will be dependent upon the position of the girder in the dumper frame and will be correct for any position of the girder.

My invention may be further briefly sum-

marized as consisting in certain novel combinations and arrangements of parts which will be described in the specification and set forth in the appended claims.

5 In the accompanying sheets of drawings illustrating an embodiment of my invention, Fig. 1 is a view wholly diagrammatic, illustrating conventionally a car dumper of the lifting type with a suitable cradle hoist mechanism with my improved control applied thereto; and Fig. 2 is a view on an enlarged scale and also more or less diagrammatic, illustrating one form of the control mechanism.

10 15 Referring now to the drawings, the upright oblong figure 10 represents the frame of the dumper in which is adapted to move vertically a cradle 11 until the pivot pins carried by the cradle engage hooks carried by the vertically adjustable girder 12 (shown in full lines in one position and by dotted lines in a second position), whereupon the cradle is turned to dump the contents of the car, which is adapted to be supported on the 20 25 cradle, into the pan 13 which is carried by the girder.

Any suitable hoist mechanism may be employed for the cradle, and any approved form of rope reeving between the drum or drums 30 35 of the hoist mechanism and the cradle may be utilized. In the form illustrated, a shaft 14 which is geared to one or more driving motors (not shown) is connected by suitable gearing 15 to a pair of rope drums 16 and 17, each of which receives a two-part cable 18. These cables pass about the lower sheaves of a pair of sheave carriages 19, the upper sheaves of which receive the bights or loops of two separate cables 20 which are attached 40 to opposite ends of the cradle.

No attempt is made to show the actual trend of these several cables and all of the sheaves about which they will be passed, but in Fig. 1 the parts of the cables 20 are shown 45 as passing about sheaves 21 which it will be understood will all be mounted on the frame 10 but part being shown removed from the frame for the sake of clearness.

In Fig. 1 I have shown at the front corners 50 55 of the frame 10 the two vertical screws 22 for raising and lowering the girder 12 with its discharge pan 13. While these screws may be simultaneously turned by any suitable mechanism, which is motor operated of course, in this instance the lower ends of the screws are shown as connected by bevel gearing to a horizontal shaft 23 geared to a driving motor indicated at 24.

The control mechanism forming the subject matter of the present invention is indicated conventionally in Fig. 1 at 25. This control mechanism may assume different forms, but in one embodiment which practice has demonstrated works very effectively, 60 65 I provide a series of switches and a trip

member therefor which is in the form of a traveling nut with operative connections between this control mechanism and both the cradle hoist and the girder hoist, the connection with the cradle hoist being for the purpose of shifting the nut to operate the switches and the connection with the girder hoist being for the purpose of varying the relative positions of the nut and switches prior to the starting of the cradle hoisting operation so that the movement of the cradle is required to be accelerated and decelerated always at the proper times regardless of the position of the girder.

In the embodiment illustrated, the control mechanism includes five switches, three of which are designated 26, 27 and 28 and are designed to function during the cradle hoisting and the forward turning motion while the other two switches, designated 29 and 30, are designed to function during the return turning movement and lowering of the cradle. Any suitable form of switches may be employed, which if desired may open and close with a snap action. In this instance these two sets of switches are operated by a pair of traveling nuts 31 and 32 on a screw 33 which can be connected in any way to the cradle hoist mechanism, this connection being illustrated diagrammatically by chain and sprocket gearing designated 34 between one end of the screw 33 and shaft 14 of the cradle hoist mechanism. The purpose of the switch 26 is to slow down the upward movement of the cradle just before the pins engage the hooks about which the cradle turns in the dumping operation. The purpose of the next switch 27 is to accelerate the turning movement of the cradle, and the function of switch 28 is to stop the turning movement of the cradle in the dumping operation.

At the end of the dumping operation, the operator reverses his controller. This renders the switches 26, 27 and 28 inoperative and renders operative switches 29 and 30. On reversal of his controller, the screw 33 is driven in the reverse direction and nut 32 operates successively switches 29 and 30, switch 29 decelerating the turning movement just before the pins of the cradle leave the hooks on the girder or just before the end of the return turning movement, and switch 30 accelerating the movement of the cradle immediately after the start of the return vertical movement. The downward movement may be stopped by a limit switch which may be incorporated in the control mechanism but which may be located at some other point as for example so as to be operated by the cradle itself.

As illustrated in Fig. 2, when the nuts 31 and 32 are traveling toward the left, nut 32 opens successively switches 30 and 29 which at this time perform no function and nut 31 closes successively switches 26, 27 and 28,

and when traveling in the reverse direction, nut 31 opens successively switches 28, 27 and 26 which while being opened perform no function and nut 32 closes successively switches 29 and 30. The manner in which the closure of the several switches operates to decrease or increase the rate of movement of the cradle is immaterial to my invention inasmuch as this will depend upon the form of the electrical equipment utilized in operating the dumper. They may control resistances or equivalent means which in any desired manner control the torque and rate of movement of the driving motors, or they may suitably control the output of a motor driven generator which supplies current to the driving motors.

It is obvious that if the pan girder is elevated, switches 26, 27 and 28 must be closed later in the cycle of operations than before and the same is true of switches 29 and 30 on the return and if the pan girder is lowered, the switches must function earlier in the cycle of operations. Notwithstanding this variable, I am enabled by my invention to operate the switches automatically and at the proper times for any position of the girder by coupling a part of the control mechanism to the girder hoist mechanism so that a given vertical adjustment of the girder, either up or down, will vary by the proper amount the normal relative positions of the traveling nuts and switches prior to the start of the dumping movement. That is to say, the movement of the girder shifts relatively an appropriate amount the switches and nuts, and in this instance the switches are shifted relative to the nuts. To bring this about, they are mounted on a movable carriage 34 which is normally stationary and is moved only when the pan girder is shifted, this carriage, in this instance, being moved by a screw 35 which, as shown, is alongside screw 33 and is mounted with the latter on a common support 36. One end of this screw is connected to an appropriate part of the girder hoist mechanism so that it will be turned so as to shift the carriage 34 whenever the pan girder is moved, and while any suitable driving or connecting means may be employed, this is illustrated conventionally in Fig. 1 in the form of shafting and bevel gears designated as a whole by the reference character 37 arranged so as to connect the screw 35 to the shaft 23 which turns the girder adjusting screws 22.

Thus it will be seen that with my improvements it is only necessary for the operator to shift his controller to start the cradle upward and then to reverse his controller to start the return movement, the necessary slowing down and speeding up taking place automatically at the right times in the cycle of operations regardless of any movement which may be imparted to the pan girder.

While I have shown my invention diagrammatically and have indicated one way of obtaining the results, other ways may occur to one skilled in the art, and I, therefore, aim in my claims to cover all modifications which do not involve a departure from the spirit and scope of my invention in its broadest aspects.

Having thus described my invention, what I claim is:

1. In combination with a car dumper having a cradle adapted to be elevated therein and then turned, and having a vertically adjustable discharge pan for receiving the contents of a car, a hoist for the cradle, a hoist for the pan, and a control mechanism for the cradle hoist connected to the pan hoist.

2. In combination with a car dumper of the lifting type having a cradle, a discharge pan, a hoist for elevating and turning the cradle, a hoist for changing the elevation of the pan, a control mechanism for the cradle hoist composed of relatively movable members, and movement transmitting means between the pan hoist and said control mechanism to vary the relative position of said members of the latter.

3. In combination with a car dumper of the lifting type having a cradle and a vertically adjustable discharge pan, a hoist for elevating and turning the cradle, a hoist for varying the position of the discharge pan, a control mechanism for the cradle hoist and movement transmitting connections from both the cradle hoist and the pan hoist to said control mechanism.

4. In combination with a car dumper having a cradle and a discharge pan, a cradle hoist for elevating and turning the cradle, a pan hoist for varying the position of the pan in the dumper, a control for the cradle hoist including switching means and a travelling member connected to the cradle hoist, and a connection between the pan hoist and the control mechanism for varying the normal relative positions of said switching means and travelling member.

5. In combination with a car dumper having a cradle and a discharge pan, a cradle hoist for elevating and turning the cradle, a pan hoist for varying the position of the discharge pan, control mechanism for the cradle hoist including a series of switches and a travelling nut connected to the cradle hoist for successively operating the switches, and a connection between the control mechanism and the pan hoist for varying the normal relative positions of the travelling nut and switches as the height of the pan is adjusted.

6. In combination with a car dumper of the lifting type having a cradle and a vertically adjustable cross girder carrying a discharge pan, a cradle hoist for elevating the cradle to a height depending upon the

position of the girder and for then turning the cradle, a girder hoist for varying the height of the girder and pan, a control mechanism for the cradle hoist comprising a plurality of successively operated switches, a screw connected to the cradle hoist and having a travelling nut for operating the switches, and a movement transmitting connection between a part of said control mechanism and the girder hoist to adjust the normal relative positions of said switches and nut when the position of the girder is adjusted.

7. A control mechanism for the cradle hoist of car dumpers of the lifting and turning type having means for varying the height of discharge, said control mechanism comprising a series of switches adapted to be successively operated for accelerating and decelerating the cradle hoist, a travelling member for actuating the same, and means for automatically varying the time of operation of said switches in accordance with a variation in the height of discharge.

8. A mechanism for remotely controlling the cradle hoist of car dumpers of the lifting type having means for varying the height of discharge comprising a series of control members adapted to be successively and automatically operated for accelerating and decelerating the speed of operation of the hoist, an actuator for said control members, means for relatively moving said actuator and said control members for normal operation of the control mechanism, and means for varying the initial relative positions of said control members and said actuator in accordance with variations in the height of discharge.

9. In combination with a car dumper having a cradle adapted to be elevated therein and then turned, a discharge pan vertically adjustable for varying the height of discharge, a hoist for the cradle, a control mechanism remote from the pan and cradle for automatically accelerating and decelerating the movement of the cradle at different points of the dumping cycle, and means responsive to the vertical adjustments of the discharge pan for changing the times of operation of the control mechanism.

10. In an electric car dumper, means including an electric motor for raising the car from an initial position, means for causing the car to tilt when it has been raised to a predetermined point, an apron for directing the delivery of the material from the car, means for adjusting the position of said apron, and means including limit switch mechanism jointly operated in response to the movements of said apron and car for effecting a reduction in the speed of said motor prior to the initiation of said tilting operation and then an increase of the speed

of said motor after the initiation of said tilting operation.

11. In an electric car dumper, means including an electric motor for raising the car from an initial position and for lowering the car to said initial position while maintaining the car substantially horizontal, means for causing the car to tilt when it has been raised to a predetermined point and for causing the car to assume its substantially horizontal position when said motor operates to lower the car to its initial position, an apron for directing the delivery of the material from the car, means for adjusting the position of the apron, limit switch mechanism operated synchronously with said motor for automatically reducing the speed of said motor prior to the initiation of the tilting movement of the car and also for an interval prior to the restoration of the car to the horizontal position, and means operated in accordance with the operation of said adjusting means for automatically adjusting the said mechanism to take into account the adjustment of the position of the apron.

12. In an electric car dumper, a cradle, a car to be dumped secured therein, an apron for directing the delivery of the material from the car, an adjustable support for said apron, relatively movable cooperating elements carried respectively by said apron and cradle which form a hinge joint about which the cradle is tilted to dump the material from the car, means including an electric motor for raising the cradle until said elements engage to form said hinge joint and then further raise one end of the cradle about said joint to spill the material from the car, an electric control for said motor including a limit switch mechanism operated synchronously with said motor for effecting a temporary automatic reduction of the speed of said motor prior to the engagement of said hinge elements and also prior to the disengagement thereof, and means for operating said mechanism in accordance with the movement of said support to adjust the times of said automatic speed reductions in dependence on the adjustment of the support.

In testimony whereof, I hereunto affix my signature.

ARTHUR F. CASE.
